DESIGN FOR A TUBE OR SIMILAR CONTAINER

Ferdinand W. Nitardy, Brooklyn, N. Y., assignor to E. R. Squibb & Sons, New York, N. Y., a corporation of New York

Application October 19, 1935, Serial No. 59,133

Term of patent 14 years

To all whom it may concern:

Be it known that I, Ferdinand W. Nitardy, a citizen of the United States, residing at Brooklyn, in the county of Kings and State of New York, have invented a new, original, and ornamental Design for a Tube or Similar Container, of which the following is a specification, reference being had to the accompanying drawing, forming part thereof.

In the drawing:

Fig. 1 is a top view of the tube or similar container showing my new design;

Fig. 2 is a front view; and

Fig. 3 is a side view.

I claim:

The ornamental design for a tube or similar container substantially as shown.

FERDINAND W. NITARDY.
